UNITED STATES PATENT OFFICE.

ALEXANDER BOYNTON, OF SAN ANTONIO, TEXAS.

BAILER BOTTOM.

Application filed May 8, 1922. Serial No. 559,362.

To all whom it may concern:

Be it known that I, ALEXANDER BOYNTON, a citizen of the United States, and resident of San Antonio, in the county of Bexar and State of Texas, have invented certain new and useful Improvements in Bailer Bottoms, of which the following is a specification.

This invention relates to bailer bottoms especially adapted for use in oil and water wells.

Briefly stated an important object of this invention is to provide a bailer wherein the vertical pressure produced by downward thrust of heavy bailer is utilized as a means to open the bailer for the reception of the mud and wherein the pressure of the mud surrounding the bailer results in the rapid filling of the same.

The invention aims to provide a bailer wherein the inlet and outlet openings are in the sides of the bailer so that when the bailer is withdrawn and set on the derrick sill, the free discharge of the mud will not be interfered with by inaccessible parts.

Also by having the openings in opposite sides of the bailer a steam or water hose may be inserted in one of the openings for loosening the mud which may be lodged within the bailer and the mud thus loosened is discharged out through the other opening. Likewise the steam from the steam hose is not returned through the opening through which it enters, but is passed out through the oppositely arranged opening along with the mud.

A further object of the invention is to provide a bailer which will remain closed until the heavy mud in the bottom of the well is encountered and which will not open as a result of encountering the lighter mud which is located above the heavier mud. In this manner by removing the heavier mud first, the lighter mud and fluid above is left in the well to become mixed with the heavy mud below as the bailing process is continued, thus avoiding the necessity of washing and pouring in water.

A further object is to provide a well bailer which is of highly simplified construction, reliable in use and in which the loss of any of the parts is prevented.

Other objects and advantages of the in-

vention will be apparent from the following description.

In the accompanying drawing forming a part of this application and in which like numerals are employed to designate like parts throughout the same,

Figure 1 is a side elevation of the improved bailer,

Figure 2 is a vertical sectional view through the same,

Figure 3 is a side elevation of a sleeve embodied in the invention.

Figure 4 is a vertical section thru the sleeve illustrated in Figure 3.

In the drawing wherein for the purpose of illustration is shown a preferred embodiment of the invention the numeral 30 designates an inner or mud receiving sleeve having its rear end formed with a coupling 31 adapted for connection with the lowering means. An outer sleeve 32 is slidable on the inner sleeve and is limited in its movement by means of a pair of oppositely arranged set screws 33 carried by the inner sleeve and arranged in longitudinally extending slots 34. The set screws 33 not only serve as a means for limiting the sliding movement of the outer sleeve but also as a means for connecting a bushing 35 to the inner sleeve. Further, the set screws 33 of which there are two securely and positively connect the threaded end of a lifter shaft 36 to the bushing 35 as the set screws positively engage the forward portion of the lifter shaft.

As illustrated in Figure 2 the forward portion of the lifter shaft 36 is formed with a head 37 which is received within a recess 38 in the forward portion of the cutter sleeve.

In carrying out the invention the outer sleeve is formed with oppositely arranged grooves 39 which terminate at their rear ends in openings 40 adapted for registration with openings 41 in the forward portion of the inner sleeve. However the openings 40 of which there are two register with the openings 41 only when the outer sleeve 32 is forced rearwardly either through engagement with the heavy mud or by engagement with a tubular member exteriorly of the well. That is to say when it is desired to discharge the mud from the bailer, the tapered forward end of the outer sleeve is

- introduced into the tubular member which will allow the inner sleeve 30 and the lifter shaft 36 to advance, whereupon the openings 40 and 41 may be brought into registration.
- 5 It is quite obvious that the engagement of the head 37 with a flat surface such as the floor of the derrick would prevent the outer sleeve from retracting and aligning the openings 40 and 41. A coiled spring 42 is 10 confined between the coupling member 31 and the rabbeted rear end of the outer sleeve and serves as a means for normally holding the parts in the position illustrated in Fig. 2.
- 15 In operation the bailer is introduced into the well and passed through the major portion of the lighter mud which of course is above the heavier mud. As the bailer descends the mud in seeking an avenue of escape passes upwardly and thereby exerts a 20 pressure which facilitates the introduction of the mud into the bailer. When slots 40 and 41 are caused to register the pressure of the heavy mud on the outer section causes 25 the same to move rearwardly whereupon the openings 40 and 41 are brought into registration. As previously stated, the pressure created by the downward movement of the bailer operates to cause the mud to rush 30 violently into the bailer when the openings 40 and 41 are in registration. The weight of the lighter mud above added to weight of 35 bailer forces the heavier mud into the bailer. This loading process can be made still more effective and certain by the repeated spudding of the bailer on bottom.
- When the bailer is loaded with mud it may be withdrawn and quickly dumped by setting the tapered lower end of the outer sleeve 40 on a pipe or other member having an opening and the weight of the inner section and the mud will cause the same to descend whereby the openings 40 and 41 are brought 45 into registration. All of this can be accomplished without removing the bottom, tinkering with springs, pins or slots, and without fishing around in the slush pit to pick up the disconnected bottom, as is the case with other well known bailer bottoms.
- 50 In churning to dump, the slots are open at the instant of impact, thus allowing the mud to escape, being different in this respect also from the bailer bottoms now employed. In most of the bailers now in use, the mud 55 is discharged through the lower end and consequently the mud cannot be freely discharged at the instant of impact.
- It will be further observed that a water or steam hose may be introduced into the 60 bailer through one of the openings and the stiff mud may be melted or discharged through the other opening thereby preventing the steam from coming back upon hands of operator through the opening by which 65 it entered.

In use the bottom section or outer sleeve cannot be lost because the lifter shaft 36 positively connects the outer sleeve to the inner sleeve and cooperates with the set screws 33 in this respect.

70 With reference to the foregoing description taken in connection with the accompanying drawings, it will be seen that a mud bailer constructed in accordance with this invention may be readily and conveniently 75 operated for removing the mud from the bottom of an oil well or any other well. The connection between the parts precludes the possibility of loss of the outer section and consequently the necessity of frequently fishing 80 in the bottom of the well for lost parts is overcome to a large extent.

It is to be understood that the form of the invention herewith shown and described is to be taken as a preferred example of the 85 same and that such minor changes in arrangement and construction of parts may be made as will remain within the spirit of the invention and the scope of what is claimed.

90 Having thus described the invention, what I claim is:—

1. A bailer for wells comprising inner and outer sleeves having mud passages adapted for registration, the outer sleeve 95 having its forward portion tapered and provided with an end wall formed with a centrally arranged opening, a lifter shaft extended through the opening in the forward end wall of said outer sleeve, a bushing carried by the inner sleeve and engaged by said lifter shaft, set screws connecting said bushing to said inner sleeve and connecting the lifter shaft to the bushing, said set screws also providing a sliding connection between the inner and outer sleeves, and a spring urging said outer sleeve to its advanced position on said inner sleeve.

100 2. A bailer for wells comprising inner and outer sleeves having mud passages adapted for registration, the outer sleeve having its forward portion tapered and provided with an end wall formed with a centrally arranged opening, a lifter shaft extended through the opening in the forward end wall of said outer sleeve, a bushing carried by the inner sleeve and engaged by said lifter shaft, set screws connecting said bushing to said inner sleeve and connecting the lifter shaft to the bushing, said set screws also providing a sliding connection between the inner and outer sleeves, a spring urging 105 said outer sleeve to its advanced position on said inner sleeve, and a coupling threaded on the rear end of the inner sleeve and constituting an abutment for one end of said spring.

110 3. A bottom for well bailers comprising inner and outer sleeves, the inner sleeve being extended a substantial distance rear- 115 120 125 130

- wardly of the outer sleeve, said inner and outer sleeves being provided with pairs of oppositely arranged openings adapted for the passage of mud, a bushing threaded 5 into the inner sleeve, set screws connecting said inner sleeve to said bushing, said outer sleeve being provided with slots receiving said set screws whereby a sliding connection is provided between the inner 10 and outer sleeves, the forward portion of said outer sleeve being formed with grooves terminating at the openings in the outer sleeve, the forward portions of said grooves being flared.
- 15 4. A bailer for well bottoms comprising inner and outer sleeves, the inner sleeve being extended a substantial distance rearwardly of the outer sleeve, said inner and outer sleeves being provided with pairs of 20 oppositely arranged openings adapted for the passage of mud, a bushing threaded into the inner sleeve, set screws connecting said inner sleeve to said bushing, said outer sleeve being provided with slots receiving 25 said set screws whereby a sliding connection is provided between the inner and outer sleeves, the forward portion of said outer sleeve being formed with grooves terminating at the openings in the outer 30 sleeve, and a spring urging said outer sleeve to its advanced position.
5. A bailer comprising an outer sleeve having its opposite sides formed with openings and with longitudinally extending 35 grooves communicating with said openings, an inner sleeve arranged within said outer sleeve and having openings adapted for communication with said first named openings, and means establishing a sliding connection between the inner and outer sleeves.
- 40 6. A bailer comprising an outer sleeve having its opposite sides formed with openings and with longitudinally extending grooves communicating with said openings, 45 an inner sleeve arranged within said outer sleeve and having openings adapted for communication with said first named openings, means establishing a sliding connection between the inner and outer sleeves, and 50 a lifter shaft having connection with the forward portion of said inner sleeve and formed with a head engaging the forward end of said outer sleeve whereby to maintain a constant connection between the inner and outer sleeves. 55
7. An apparatus of the character described comprising inner and outer slidably connected sleeves having openings adapted for registration, the outer sleeve being formed with material conveying grooves 60 communicating with the openings in the outer sleeve.
8. An apparatus of the character described comprising inner and outer slidably connected sleeves having openings adapted 65 for registration, the outer sleeve being formed with material conveying grooves communicating with the openings in the outer sleeve, and a lifter shaft rigidly connected to one of said sleeves and having a 70 stop element in the path of travel of the other sleeve.
9. An apparatus of the character described comprising inner and outer slidably connected sleeves having openings adapted 75 for registration, the outer sleeve being formed with material conveying grooves communicating with the openings in the outer sleeve, a lifter shaft rigidly connected to one of said sleeves and having a stop element in the path of travel of the other sleeve, and means cooperating with said stop element to permit sliding movement of the sleeves with relation to each other.
10. An apparatus of the character described comprising inner and outer sleeves having mud passages adapted for registration, a bushing confined in one of the sleeves, a stop element threaded into said bushing and having means located in the 80 path of travel of one of said sleeves to limit the sliding movement of the sleeves with relation to each other, and a set screw threaded through one of said sleeves, and 85 said bushing and engaging said stop element whereby to connect the stop element to the bushing, said stop element being provided with a head and one of the sleeves being provided with a slot receiving the head. 90 95

ALEXANDER BOYNTON.
